UNITED STATES PATENT OFFICE.

JOHN T. HOYT, OF HAZLETON, PENNSYLVANIA, ASSIGNOR TO UNITED FILTERS CORPORATION, OF NEW YORK, N. Y., A CORPORATION OF DELAWARE.

APPARATUS FOR SEPARATING LIQUID FROM PULP FIBERS.

Application filed February 1, 1924. Serial No. 689,938.

This invention relates to the paper making art, and to other fields wherein the separation of solid from liquid material is desired, more especially to the step of separating the liquid from the pulp fibers for the purpose of weighing or the like, in the various washing and changing operations which the pulp undergoes prior to being formed into a sheet of paper, or for the recovery of waste pulp from the "white liquor" or mill effluent.

It is the object of the invention to provide an apparatus which will operate continuously and efficiently to extract the liquid from the pulp fibers and deliver pulp at any desired consistency from the solution.

Another object of the invention is to provide an apparatus by which the pulp fibers and pulp liquor may be effectively separated without having the continuous operation thereof interrupted by the gummy and resinous constituent of the pulp liquor which tends to clog the pores of an ordinary filter when used for thickening wood pulp.

Another object of the invention is to provide an improved separating medium for continuous filters for separating the pulp fibers and other solids from the pulp or sludge liquor, which will permit the passage of the pulp liquor therethrough but will largely prevent passage of the pulp fibers, and which will not become clogged or impervious to the passage of the pulp or sludge liquor therethrough by the resinous or gummy content of the sludge or pulp liquor.

Another object of the invention is to provide means for stripping the deposited pulp cake from the surface of the separating medium and for simultaneously cleaning any adhering matter from the surface of the separator.

In connection with this latter object, a particularly important feature of the invention is the use of a separating medium for the pulp fiber and pulp liquor, consisting of a perforated plate of sheet metal or other suitable material, the perforations of which will permit effluent water or liquid to pass therethrough but are so small that the pulp fibers mat thereon and do not permit the pulp to pass therethrough, the material of the sheet metal plate being of such a nature that the resinous or gummy content of the pulp or other liquor does not accumulate thereon or stop the pores thereof.

Various other objects and advantages will

appear as the description of the invention proceeds.

Referring now to the drawings which will illustrate one form of embodiment of the invention,

Fig. 1 is an end view partially in section of one form of apparatus embodying the invention.

Fig. 2 is a side view of the apparatus shown in Fig. 1.

Fig. 3 is a detail view illustrating the operation of the pulp removing and cleaning device.

Fig. 4 is a sectional view on an enlarged scale of a portion of the separating surface.

Fig. 5 is a similar view showing how the separating medium may be applied to the apparatus.

Fig. 6 is a detail illustrating the passages between the vacuum compartments.

Figs. 1 and 2 illustrate an apparatus which may embody my invention, patterned after the somewhat conventional drum type rotating filter. This apparatus comprises a drum 1, adapted to rotate through a tank 2 resting on suitable supports 3 and containing the pulp solution or other material being separated.

The rotating drum comprises suitable rim portions 6 supported by the radial arms 7 from trunnions which are rotated in suitable bearings on the tank 2 by means of a worm wheel 12, driven by the worm 14, on the end of the shaft 13, the other end of which is provided with pulleys 15 by means of which it may be driven by a belt connection or the like from any suitable source of power.

A plurality of wood or metal staves 20 extend across the rim portions 6 of the drum 1 so as to form a substantially airtight partition between the inner and outer portions of the drum, and on the staves 20 a plurality of division or spacing strips 21 running longitudinally and circumferentially of the drum are positioned.

Certain of the spacing strips 21 are of solid construction so as to divide the surface of the drum into a plurality of separate vacuum compartments while others are provided with cut-out portions 21^a, as illustrated in Figs. 1 and 6 to permit the vacuum to be communicated and the pulp liquor to be drawn through the same into the nearest vacuum pipe 28.

Over the spacing strips 21 the separating

medium 22 consisting of perforated strips of sheet metal or other suitable material are secured by any suitable means to effect a separation of the pulp liquor from the pulp fibers as the drum rotates through the solution in the tank.

In the practice of my invention, I have found it preferable to apply the separating medium of perforated sheet metal in strips 22^a extending longitudinally of the drum and to secure the strips by means of screws or the like 23 along the edges thereof, to the spacing strips 21.

For efficient separation of the pulp fibers from the pulp liquor I have found it desirable to make the holes or perforations 24 in the separating medium of very small diameter, approximately .020 of an inch, and to effect rapid withdrawal of the liquid I provide about 600 of these holes per square inch of the separating medium. However, it is to be understood that the invention is not limited to perforations of any particular size or number, but that the size and number will vary depending upon the nature of the material being concentrated.

The space provided between the outer surface of the staves 20 and the separating medium is provided with suitable vacuum connections, such as pipes 28 which extend through one of the trunnions 8 and are connected to a suitable rotary plug valve 30 such as is described in the patent of O. J. Salisbury, 1,259,139, Mar. 12, 1918, a vacuum connection 32, by means of which the air in said space may be exhausted to draw the liquid through the separating medium.

If desired, the valve 30 may also be provided with a pressure connection 31, and suitable pressure pipes may be extended to the spaces between the drum and separating medium whereby air under pressure may be forced through the separating medium to dislodge the pulp if necessary.

In order to effect a complete removal of the pulp from the surface of the drum, and to clean the separating medium preparatory to reimmersing it in the pulp solution, I provide a rotating brush or roller 33 which extends longitudinally of the drum 1 at the point where it enters the tank 2. This brush may be provided with bristles or may be a felt covered roller, and is driven to rotate so that the engaging faces of the drum 1 and the brush move in opposite directions by means of a sprocket chain 34 driven from the sprocket wheel 35 on a stud shaft 36 journaled on side of the tank 2, a belt 37 and a pulley 38 being provided to turn the shaft 36.

In order to clearly illustrate the invention, the separating medium has been illustrated with holes of appreciable size but it is to be understood that when holes of .020 inch in diameter are provided in the separator medi-

um, they will appear of much smaller size on the actual embodiments of the invention.

In the operation of the apparatus, the drum 1 is rotated by means of the pulley 15 and as it moves through the pulp solution, the suction from the vacuum line 32 is communicated through the vacuum pipes 28 to the separating medium 22 and the pulp liquor is drawn through the perforations in the separating medium and discharged from the pipe 32, while the pulp fibers are deposited as a layer on the surface of the drum. As the drum continues to rotate the pulp is moved out of the solution and over the top of the drum. Depending upon the arrangement of the valve 30 the suction may if desired, be continued after the pulp cake is removed from the solution, to draw air through the pulp cake and reduce the moisture content thereof or the air under pressure from the pipe 31 may be turned on when desired to loosen the pulp cake from the surface of the drum.

As the drum continues to rotate, the pulp reaches the brush 33 which is rotated to strip the pulp in a substantially continuous sheet from the drum and direct it onto the apron 39 from which it passes into a suitable receptacle.

It is to be noted here that the brush or roller 33 is pressed against the surface of the drum to give a complete cleaning effect to the sheet metal separating plate 22 so as to remove any adhering pulp fibers or resinous material therefrom to substantially prevent clogging of the perforation 23 as the drum continues to rotate through the pulp solution. After three or four months' continuous service, the perforations may become clogged, in which case it is a simple matter to clean the same by directing a jet of steam against the surface of the drum.

It will be seen that I have provided an apparatus capable of rapidly and continuously dewatering the pulp fibers contained in the pulp solution, and which will not readily become clogged by the resinous or gummy content of the pulp liquor, or other liquor being filtered.

In the operation of the dewatering apparatus if the suction through the separating medium is cut off about the time the pulp leaves the solution the pulp will contain 90 to 95% of water when discharged, however, by continuing the suction until the brush 33 is reached the water content can be reduced to about 80% if desired.

Although I have herein shown and described only certain specific forms of embodiment of the invention, it will be readily understood that many changes and modifications may be made therein within the scope of the following claims, without departing from the spirit and scope of the invention and that the invention is not confined solely to the fil-

tration of paper pulp but may be used in other fields where the sticky, gummy or resinous nature of the sludge causes ordinary filter fabrics to clog up too rapidly for efficient 5 service, it being my intention to claim the invention as broadly as the state of the prior art will permit.

I claim—

1. In an apparatus for separating liquid 10 from pulp fibers, a receptacle for the pulp solution, a drum extending into the receptacle, means to rotate the drum, a perforated smooth surfaced separating plate on the surface of the drum, means to pass the liquid 15 through said perforations to deposit a layer of pulp on said perforated plate in the solution, and means comprising a rotating brush to remove the deposit from the perforated plate in a substantially continuous sheet.
2. In an apparatus for separating liquid 20 from pulp fibers or the like, a receptacle for the solution, a drum extending into the receptacle, means to rotate the drum, a perforated smooth surfaced separating plate on the surface of the drum, means to pass the liquid 25 through said perforations to deposit a layer of pulp on the portion of the drum in the solution, and rotating means outside the solution for removing the layer of pulp deposited on the drum in a substantially continuous sheet.
3. In an apparatus for separating liquid 30 from pulp fibers or the like, the combination of a receptacle for the pulp solution, a drum extending into the solution, means to rotate the drum, a perforated sheet metal plate on the surface of the drum, means to create a suction inside the drum to draw the liquid 35 through the perforations and deposit a layer of pulp fibers thereon, means to cut off suction from a portion of the drum outside the pulp solution and means to completely remove the pulp fibers from said plate during 40 each cycle of filter operation.
4. In an apparatus for separating liquid 45

from pulp fibers or the like, the combination of a receptacle for the pulp solution, a drum extending into the solution, means to rotate the drum, a perforated sheet metal plate on the surface of the drum, and means 50 to create a suction inside the drum to draw the liquid through the perforations and deposit a layer of pulp fibers thereon, means to cut off the suction from the portion of the drum outside the solution, and a brush contacting with the surface of the drum and 55 rotating in a direction to remove the pulp layer in a substantially continuous sheet and clean the surface of the drum.

5. In an apparatus of the type described, 60 the combination of a receptacle, a drum extending into the receptacle, a separating medium on said drum composed of perforated sheet metal plate, containing approximately 600 perforations per square inch, each perforation being about .020 of an inch in diameter, 65 means to rotate said drum, means to cause suction on the inside of the perforated plate to effect separation of the liquid and solid matter in said receptacle, means to cut off the 70 suction to a portion of the plate outside the receptacle and means to completely remove the pulp fibers from the perforated plate once each rotation of the drum.

6. In an apparatus of the type described, 75 the combination of a receptacle, a drum extending into the receptacle, a separating medium on said drum composed of perforated sheet metal plate, containing approximately 600 perforations per square inch, each perforation being about .020 of an inch in diameter 80 means to rotate said drum, means to effect separation of the liquid and solid matter in said receptacle and deposit the solid material on said drum, and means outside said receptacle, rotating in a direction to remove the solid material from the drum.

In testimony whereof I have affixed my signature to this specification.

JOHN T. HOYT.
